UNITED STATES PATENT OFFICE

151,657

DESIGN FOR A PUZZLE OR SIMILAR ARTICLE

Anita M. Renault, Chicago, Ill.

Application July 27, 1946, Serial No. 132,030

Term of patent 7 years

(Cl. D34—15)

To all whom it may concern:

Be it known that I, Anita M. Renault, a citizen of the United States, residing at Chicago, in the county of Cook and State of Illinois, have invented a new, original, and ornamental Design for a Puzzle or Similar Article, of which the following is a specification, reference being had to the accompanying drawing, forming a part thereof.

In the drawing:

Fig. 1 is a top plan view of a puzzle or similar article showing my new design, and
Fig. 2 is an end elevational view thereof.

I claim:

The ornamental design for a puzzle or similar article, substantially as shown.

ANITA M. RENAULT.
